DESIGN FOR A TOY BUILDING LOG

Nils I. Paulson, Chicago, Ill., assignor to Halsam Products Company, Chicago, Ill., a corporation of Illinois

Application October 31, 1935, Serial No. 59,299

Term of patent 14 years

To all whom it may concern:

Be it known that I, Nils I. Paulson, a citizen of the United States, residing at Chicago, in the county of Cook and State of Illinois, have invented a new, original, and ornamental Design for Toy Building Logs, of which the following is a specification, reference being had to the accompanying drawing, forming part thereof.

In the drawing, the figure is a perspective view of a toy building log embodying my new design.

I claim:

The ornamental design for a toy building log substantially as shown.

NILS I. PAULSON.
